UNITED STATES PATENT OFFICE.

LEE VAN FLEET, OF PARKERSBURG, IOWA.

CHAIR.

1,391,222.

Specification of Letters Patent. Patented Sept. 20, 1921.

Application filed October 6, 1919. Serial No. 328,779.

To all whom it may concern:

Be it known that I, LEE VAN FLEET, a citizen of the United States, residing at Parkersburg, in the county of Butler and

5 State of Iowa, have invented certain new and useful Improvements in Chairs, of which the following is a specification.

This invention relates to an article of furniture, and more particularly to a combined 10 chair and table, particularly designed for use by typists, or stenographers, and an object of the invention is to provide a combined chair and table of this nature which is strong and sturdy of construction, comprising 15 a pedestal which rotatably supports a chair bottom and back and from which a standard is supported by means of a circuit bracket or supporting arm structure, which standard in turn rotatably supports the carrying arm of the table structure which may 20 be utilized for supporting a typewriter or for the purpose of taking notes or dictation by a stenographer.

Another object of this invention is to provide 25 a combined chair and table structure as specified, which will take up comparatively little room and which may be conveniently located so that the person dictating may walk about without interfering in any way with 30 the stenographer, and which will also permit the use of the dictator's desk for permitting the spreading out of the documents or 35 analogous material being considered during dictation, allowing these documents or other material to be freely scanned by the dictator without interfering in any way with the efficiency 40 of the stenographer, in that the improved chair and table will eliminate the necessity of using a part of the dictator's desk for supporting a stenographer's note book.

Other objects of the invention will appear 45 in the following detailed description taken in connection with the accompanying drawing, forming a part of this specification, and in which drawing:

Figure 1 is a side elevation of the improved chair and table.

Fig. 2 is a detail section through the chair

and table structure illustrating the mounting of the seat of the chair, and

Fig. 3 is a detail section illustrating the mounting of the table.

Referring more particularly to the drawings, the improved combined chair and table 55 comprises a pedestal 5, which is preferably hollow and is of such size as to form a secure sturdy support. The pedestal 5 preferably has an enlarged base 6 formed upon its lower end, and it is provided with an 60 annular shoulder 7 intermediate its ends, against which the under edge of a collar 8 rests. This collar 8 is formed upon the free end of the arm 9 of a forked supporting bracket structure 10 which comprises a horizontal arm 11 as well as a diagonal or angled arm 9, these arms merging near their outer ends and terminating in a collar 12 which supports a suitable standard 13. An upstanding bracket arm 14 is formed upon the 70 bracket structure 10 near its outer end, and this upstanding arm 14 is provided with a collar 15 which engages about the standards 13 in spaced relation to the collar 12. The collar 15 also forms a support upon which 75 the collar 16 rests. This collar 16 is formed upon the free end of the angled arm 17, of the supporting arm structure 18. This supporting arm structure 18 comprises, besides the angled arm 17 a horizontal arm 19 which 80 has a collar 20 formed upon one end thereof, and alining with the collar 16. This collar 20 is mounted upon the upper end of the standard 13. The supporting arm or bracket structure 18 has a collar 21 formed upon its 85 end, opposite to the end upon which the collar is formed. The collar 21 is provided with a threaded bore 22 in which is threadably engaged a stud 23. The stud 23 has a wrench head 24 formed thereon, against the 90 upper surface of which is the hub portion 25 of the supporting bracket or miter 26. This miter structure 26 is connected to a portion of the stud 23 which projects above the wrench head 24, by a set screw 27, the 95 head of which is countersunk in the hub portion 25 while the stem is threadably engaged in an axial threaded recess 28 formed in the

upwardly extending end of the stud 23 as clearly shown in Fig. 3 of the drawings. A table or supporting board 29 is mounted upon the bracket structure 26 and is attached thereto in any suitable manner, such as by screws or analogous fastening devices 5. By rotating of the stud 23 through the medium of the wrench head 24, the elevation of the table 29 may be regulated as desired. 10 The standard or pedestal 5 has its upper end reduced in diameter, forming a shoulder 31, against which the collar 32 which is formed upon the inner end of the horizontal arm 11 rests. This reduced end of the pedestal 5 is also internally screw threaded as shown at 33, and it receives therein a nut 34, the wrench head 35 of which engages against the upper end of the pedestal 5 and the upper edge of the bar 32 as clearly shown in 15 Figs. 1 and 2 of the drawings. The nut 35 is provided with an axial bore 36, and with ball races 37 at its upper and lower ends, surrounding said axial bore 36. The stem 38, of the seat structure 39 of the chair projects 20 through the bore 36, and it has a washer 39 mounted upon its lower end which is provided with a ball race 40 adapted to engage against the bearing barrels 41 in the lower ball race 37 to form a ball bearing connection 25 between the stem 38 and pedestal 5 at the lower end of the stem. This washer 39 is held in place on the stem 38 by the nut 42. The stem 38 has a spider structure 43 formed 30 upon its upper end which forms the support for the seat bottom 39 and it is also provided with an enlargement 44, at the junction of the spider arm and the stem, which coacts with the ball race 37 in the upper end of the nut 35 for confining the bearing balls 45, to 35 form a ball bearing or anti-friction engagement between the seat structure and the nut 35 at the upper end of the latter.

The seat portion 39 may be constructed in any desirable manner, and it has a back 40 of any preferred construction attached thereto in the usual manner. The connection between the stem 38 and pedestal 5 permits the chair structure to be rotated about the pedestal as an axis and the connection of the bracket or supporting structure 18 with the standards 13 will permit the table to be swung about upon the axis of the standard 13 and by providing the base bearing collars 16 and 20 the use of thumb 45 screws or analogous fastening devices is eliminated in that the two bearing collars will provide sufficient friction to prevent accidental free rotary movement of the supporting bracket 18 upon the standard, but 50 will allow comparatively easy movement of the supporting arm under manual force. The above is also true of the connection of the supporting bracket 10 with the pedestal 5. The position of the arms 17 and 19 and 55 also 9 and 11 will prevent sagging of any

part of the table structure with respect to the pedestal 5.

Changes in details may be made without departing from the spirit of this invention, but;

I claim:

1. In a device as set forth, the combination of a pedestal, a nut threaded on the upper end of said pedestal and provided with an axial bore, a chair seat, a stem carried by and depending from the center of the under surface of said chair seat, ball races formed in the upper and lower ends of said nut and surrounding said axial bore, bearing balls in said ball races, means carried by said stem for confining said bearing balls in said ball races and to provide anti-friction bearings between the stem and nut. 75

2. In a device as set forth, the combination of a pedestal, a nut threaded on the

upper end of said pedestal and provided with an axial bore, a chair seat, a stem carried by and depending from the center of the under surface of said chair seat, ball races formed in the upper and lower ends of said nut and surrounding said axial bore, bearing balls in said ball races, means carried by said stem for confining said bearing balls in said ball races and to provide anti-friction bearings between the stem and nut. 80

3. In a device as set forth, the combination of a pedestal, a nut threaded on the

upper end of said pedestal and provided with an axial bore, a chair seat, a stem carried by and depending from the center of the under surface of said chair seat, ball races formed in the upper and lower ends of said nut and surrounding said axial bore, bearing balls in said ball races, means carried by said stem for confining said bearing balls in said ball races and to provide anti-friction bearings between the stem and nut. 85

4. In a device as set forth, the combination of a pedestal, a nut threaded on the

upper end of said pedestal and provided with an axial bore, a chair seat, a stem carried by and depending from the center of the under surface of said chair seat, ball races formed in the upper and lower ends of said nut and surrounding said axial bore, bearing balls in said ball races, means carried by said stem for confining said bearing balls in said ball races and to provide anti-friction bearings between the stem and nut. 90

5. In a device as set forth, the combination of a pedestal, a nut threaded on the

upper end of said pedestal and provided with an axial bore, a chair seat, a stem carried by and depending from the center of the under surface of said chair seat, ball races formed in the upper and lower ends of said nut and surrounding said axial bore, bearing balls in said ball races, means carried by said stem for confining said bearing balls in said ball races and to provide anti-friction bearings between the stem and nut. 95

6. In a device as set forth, the combination of a pedestal, a nut threaded on the

upper end of said pedestal and provided with an axial bore, a chair seat, a stem carried by and depending from the center of the under surface of said chair seat, ball races formed in the upper and lower ends of said nut and surrounding said axial bore, bearing balls in said ball races, means carried by said stem for confining said bearing balls in said ball races and to provide anti-friction bearings between the stem and nut. 100

7. In a device as set forth, the combination of a pedestal, a nut threaded on the

upper end of said pedestal and provided with an axial bore, a chair seat, a stem carried by and depending from the center of the under surface of said chair seat, ball races formed in the upper and lower ends of said nut and surrounding said axial bore, bearing balls in said ball races, means carried by said stem for confining said bearing balls in said ball races and to provide anti-friction bearings between the stem and nut. 105

8. In a device as set forth, the combination of a pedestal, a nut threaded on the

upper end of said pedestal and provided with an axial bore, a chair seat, a stem carried by and depending from the center of the under surface of said chair seat, ball races formed in the upper and lower ends of said nut and surrounding said axial bore, bearing balls in said ball races, means carried by said stem for confining said bearing balls in said ball races and to provide anti-friction bearings between the stem and nut. 110

standards, and means for adjusting the elevation of said table structure relative to the standards.

5. In a device as set forth, the combination of a pedestal provided with an annular shoulder intermediate its ends, a second annular shoulder adjacent its upper end, collars rotatably mounted upon said pedestal and resting upon said shoulder, bracing

10 arms formed upon said collars and project-

ing laterally from the pedestals, said arms converging adjacent their outer ends, a standard supported by the outer ends of said arms, a second bracket structure mounted upon said standard, a table structure carried by said second bracket structure, and means for adjusting the elevation of said table relative to said pedestal. 15

LEE VAN FLEET.
